UNITED STATES PATENT OFFICE.

JOSEPH EUGENE FOSS, OF FLORENCE, SOUTH CAROLINA.

VALVE TAPPET.

Application filed June 14, 1922. Serial No. 568,313.

To all whom it may concern:

Be it known that I, JOSEPH EUGENE Foss, a citizen of the United States, residing at Florence, in the county of Florence and State of South Carolina, have invented certain new and useful Improvements in Valve Tappets, of which the following is a specification, reference being had to the accompanying drawings.

10 This invention relates to valve tappets, and more particularly to an improvement in the construction of the valve tappets of internal combustion engines.

An important object of the invention is 15 to provide a valve tappet which will be silent in its operation and eliminate the clicking noise occurring when the tappets have become slightly worn.

A further object of the invention is to 20 provide for proper lubrication of the valve tappet at its working engagement with its guiding sleeve.

A still further object of the invention is to provide a device of this character which 25 may be readily constructed and assembled, which provides a maximum of adjustability and which may be employed or substituted for valve tappets of engines now in use.

Other objects and advantages of the invention will become apparent throughout the course of the following description.

In the accompanying drawings wherein for the purpose of illustration is shown a preferred embodiment of my invention and wherein like reference characters designate like parts throughout;

Figure 1 is a sectional view taken through an engine showing a tappet assembly constructed in accordance with my invention; 40 and

Figure 2 is a sectional view taken through the tappet assembly.

Referring now more particularly to the drawings, the numeral 10 indicates a tubular guiding shell adapted to be engaged in a guide shell opening 11 of an engine base 12. The shell is provided adjacent its upper end with shoulders 13 adapted to abut the engine base and be secured thereto in 50 any suitable manner, as indicated at 14, so that the shell may be secured against movement with relation to the engine base. The lower end of the shell is provided with a reduced axial outlet opening 15 preferably 55 formed in a depending sleeve 16, which reduced outlet opening forms at the lower end

of the shell interiorly thereof an upwardly directed shoulder 17, the purpose of which will hereinafter appear.

The numeral 18 indicates a valve tappet 60 as a whole comprising upper and lower sections 19 and 20 connected by an enlarged collar 21, the periphery of which slidably embraces the inner face of the shell 10. The lower end 20 is slidably engaged in the reduced bore 15 of the shell 10 and extends therethrough for engagement by a cam 22 of a cam shaft 23 of the engine. The shell 10 and tappet 18 are preferably so connected 65 as to prevent relative rotation thereof, although this feature does not form a necessary part of my invention. In the present instance I have shown the lower end 20 of the tappet 18 as provided with a key 24 engaging in a key slot 25 formed in the depending sleeve 16. The lower face of the collar 21 forms a downwardly directed shoulder 26 facing the shoulder 17 of the shell 10 and these shoulders 17 and 26 are provided with grooves 27 receiving the ends 70 of a coil spring 28 surrounding the lower end 20 of the tappet 18 within the shell 10. The grooves 27 are provided to maintain the spring against side slip such as would bring it into engagement during its movement either with the shell 10 or the tappet 18, since such engagement would cause a squeaking during the operation of the engine. 75

The upper end of the shell 10 is exteriorly screw-threaded for engagement with a depending flange 29 formed upon a combined guide and cap nut 30. This guide and cap nut is provided with a central bore 31 receiving the upper end 19 of the tappet 18 and of slightly greater diameter than this upper end. It will be noted that the shell 10 has a two point engagement with the tappet 18 to maintain the same in alignment, the same being provided in the bore 15, and the engagement of the collar 21 with the interior of the shell, and accordingly a sliding fit between the upper end 19 of the tappet 18 and the guide and cap nut 30 is unnecessary. Engagement of the upper end of the tappet 18 with the valve or push rod for the valve may be of any desired type. In the present instance I have illustrated the tappet 18 as provided in the upper end 19 thereof with an axial screw-threaded bore 32 adapted to receive a screw-threaded lower end 33 of a push

rod 34, the push rod being provided with the usual lock nut 35 whereby it may be secured in adjusted position.

In practice the spring 28 will be made 5 of sufficient strength to elevate the working parts interposed between the cam 22 and the valve stem 36 of the valve which is to be operated. In the present showing the spring 28 will be of sufficient strength to 10 elevate its tappet 18, the push rod 34 and rocker arm 37 so as to maintain the valve engaging end of the rocker arm permanently in engagement with the valve stem 36. It will be seen that this construction will 15 very effectually eliminate lost motion in the train of mechanism between the cam and valve and will accordingly prevent the occurrence of the clicking noises now common in the operation of valve in head 20 motors.

In order to provide for proper lubrication of the tappet, I form in the shell 10 at that side thereof directed toward the crank throws 38 of the engine, openings 25 39 which will permit the passage to the interior of the shell 10 of oil thrown from the throws during their rotation. The uppermost opening 39 of the shell is so arranged as to be disposed immediately below 30 the metal of the engine base 12 at the sides of the opening 11 through which the shell 10 extends. The collar 21 is so arranged upon the tappet 18 that in its normal or lowered position its upper face is immediately 35 aligned with the lower edge of the upper opening 39 and accordingly oil thrown upon this collar from the crank throws will be spread upon the inner wall of the shell to lubricate the same. Oil entering at the lower opening 39 will pass 40 downwardly through the bore 15 and lubricate the engagement of the lower end of the tappet in this bore. Any excess oil collecting in the lower end of the shell will, of course, be drained back into the crank 45 base through the opening 39. The bore 31 of the guide and cap nut 30 is provided centrally with an enlargement or groove 40 in which is disposed a felt washer 41. The upper end of this bore is preferably 50 tapered so as to form a tapered enlargement 42 between the upper end 19 of the tappet in which oil may be introduced to pass downwardly to the felt washer 41. This washer will constantly lubricate the 55 upper end 19 of the tappet. Furthermore, oil will be thrown through the upper opening 39 against the upper end 19 of the tappet and will be wiped off and collected by the felt washer 41 to provide further lubrication.

From the foregoing it is believed to be obvious that a valve tappet constructed in accordance with my invention is particularly well adapted for the purpose for which

it is intended in that it will prevent the clicking noises ordinarily occurring in the operation of the valves and in that it provides a structure readily assembled and which will be very durable in service. It 70 is furthermore pointed out that the valve tappet 18 may be readily removed at any time for inspection or replacement without the necessity of removing the shell 10 from the engine. Many changes being possible 75 in the shape, size and arrangement of the various parts hereinbefore set forth, I do not limit myself to the specific structure thereof except as hereinafter claimed.

I claim:—

1. A tappet assembly for the valves of internal combustion engines embodying a tappet shell adapted to be secured in the shell receiving opening of the base of an engine and provided interiorly at the lower 85 end thereof with an axial opening and an upwardly directed shoulder, a tappet having its lower end slidably engaged in said opening and slidably engaging the interior wall of the shell, a downwardly directed shoulder formed on said tappet, and a compression 90 spring disposed intermediate the shoulders of the shell and tappet, the bore of the shell being unrestricted at its upper end to thereby permit removal of the tappet from the 95 shell while the shell is in position in the base of the engine.

2. A tappet assembly for the valves of internal combustion engines comprising a 100 tappet shell having its upper end open and its lower end provided with a restricted outlet forming an upwardly directed shoulder within the shell, a tappet slidably mounted within the bore of the shell removable from the shell through the upper end of the bore thereof and having its lower end extending through said restricted outlet and having a 105 sliding fit therein, a combined cap nut and guide sleeve mounted upon the upper end of said shell, a reduced upper end on said tappet extending through a bore formed in said cap nut, said tappet embodying a downwardly directed shoulder opposing the upwardly directed shoulder of the shell, and a compression spring disposed intermediate 110 said shoulders.

3. In a tappet assembly for the valves of internal combustion engines, a tappet guide shell having a central bore and provided upon its exterior with flanges whereby it may be attached to an engine base at the sides of the tappet shell receiving opening thereof, said shell being provided at the lower end thereof with a depending sleeve having a reduced bore communicating with the bore of the shell and combining with the shell to form an upwardly directed shoulder, a tappet disposed within the shell and having its lower end slidably directed through 125 and having a splined engagement with said 130

sleeve, the lower face of said tappet forming a downwardly directed shoulder opposing the shoulder of the shell, grooves formed in said shoulders in spaced relation to the tappet and shell, and a compression spring disposed within the shell surrounding the lower end of the tappet and having its ends seated in said grooves.

4. A tappet assembly for the valves of internal combustion engines comprising a tappet shell having its upper end open and its lower end provided with a restricted outlet forming an upwardly directed shoulder within the shell, a tappet having a collar 15 slidably mounted within the bore of the shell and having a lower end extending

through said reduced outlet and having a sliding fit therein, a closure for the upper end of the shell having a bore through which the upper end of said tappet extends, said bore having an enlargement forming a groove, a felt washer disposed within the groove and engaging said tappet, the lower face of said tappet collar forming a downwardly directed shoulder opposing the upwardly directed shoulder of the shell, and a compression spring disposed intermediate said shoulders.

In testimony whereof I hereunto affix my signature.

JOSEPH EUGENE FOSS.
